SHOEMAKING METHOD

Fred L. Ayers, Watertown, Mass.

Application August 12, 1937, Serial No. 158,665

1 Claim. (Cl. 12—142)

In my Patent No. 2,065,786 granted December 29, 1936, there is shown a shoe construction in which the outersole is provided with a marginal inwardly extending lip on its upper face which projects over and into interlocking engagement with an outwardly extending flange or lip element on the lasted shoe. This interlocking engagement not only acts to secure the parts together, but also to protect a cement bond between the parts inwardly of this interlocking engagement from access by foreign matter which might tend to weaken it.

The present invention relates to a shoe of the same general type and has for one of its objects to improve the method so as to facilitate the assembly of the outersole on the lasted shoe.

Another object is to provide a method by which the interlocking attachment throughout the heel end as well as the forepart may be readily effected.

A further object is to improve the cement bond between the parts.

For a more complete understanding of this invention, reference may be had to the accompanying drawings in which

Figures 1, 2 and 3 are fragmentary sections through a lasted shoe showing successive stages in the formation of the lip on the lasted shoe for interlocking connection with the outersole.

Figures 4 and 5 are similar views showing the method of applying the outersole.

Figure 6 is a view similar to Figure 2, but showing a modification.

Figure 7 is a view partly in side elevation and partly in section showing a lasted shoe and a spring heel sole adjacent thereto ready for assembly therewith.

Figures 8, 9, 10 and 11 are fragmentary sectional views showing modified innersole constructions.

Figure 12 is a view similar to Figure 7, but showing the outersole attached.

Figure 13 is a bottom plan of an outersole prepared for assembly on a lasted shoe.

Figures 14, 15 and 16 are views similar to Figure 4, but showing modifications in the structure of the lasted shoe.

Figures 17, 18 and 19 are fragmentary sectional views showing modifications in the outer sole construction.

Referring first to Figures 1 to 5, a shoe inner sole is indicated at 1 being so cut about its margin as to present an outwardly extending feather 2 at its lower edge. Upper materials including, for example, the upper 3 and the lining 4 are

lasted about the last 5 to which the innersole is temporarily secured, and the margins of the upper materials are secured to the feather 2 by stitching 6. This stitching is preferably of substantial size for a purpose which will later appear. Next, the projecting portions of the upper materials and feather 2 are trimmed off as, for example, as shown in Figure 2 at 8, to form a tapered flange or lip 10 normally extending outwardly. This portion 10 is then subjected to a pressing operation as shown in Figure 3, which deflects it downwardly with reference to the shoe sole and tends to spread the exposed stitching threads on opposite faces over substantial surface areas of this portion. This pressing may well be done by a pair of pressure rolls 11 and 12 shown in dotted lines in Figure 3, and between which the portion 10 may be extended. This action turns the lip 10 inwardly so that it is substantially wholly beneath the sole face of the lasted shoe and so that the dimensions across the shoe between the opposite edges of the rib or flange on opposite sides of the shoe come within the outline of an inwardly extending matingly tapered rib or lip 15 of an outersole for the shoe, as shown in Figure 4. The parts having been suitably coated with cement, the outersole 16, preferably pre-cut to substantially finished size, is assembled in position and the parts subjected to pressure, which returns the lip 10 toward its normally undeflected position as shown in Figure 5 and forces it beneath the lip 15 of the outersole.

Instead of trimming the lasted shoe, as shown in Figure 2, the extension 2 of the innersole may be inclined downwardly and the lower portion thereof, together with the margins of the upper materials, trimmed off substantially horizontally as at 20 in Figure 6. Such a rib 21 presents more of the upper materials and less of the innersole than does the rib trimmed in accordance with Figure 2. This rib 21 may then be temporarily distorted to substantially the vertical condition shown in Figures 3 and 4 and be subjected to pressure and returned toward its former position beneath the outersole lip 15 similarly to the lip 10.

This method of treating the lasted shoe by temporarily turning downwardly the projecting and interlocking portions also facilitates the assembly of the parts where it is desired to produce the interlock around the heel end of the shoe as well as at the forepart. For example, in Figure 7 there is shown a lasted shoe 25 having its marginal rib 26 downwardly turned as in Figure 4, 55

and to be assembled therewith is an outersole 27 provided with the inwardly directed lip member 28 entirely therearound. As shown this sole 27 is provided with a spring heel formed by a fillerpiece 29 which overlies the heel end of the sole member 27 and to the upper face of which the member 28 may be secured at the heel portion. It will be noted that the outersole 27 is in blank form, being flat, whereas the sole face of the lasted shoe 10 curves upwardly in the shank portion in accordance with the usual practice. The over-all length of the space inwardly of the member 28 lengthwise of the sole blank is therefore greater than that of the lasted shoe so that the rib 26 may 15 be easily placed between the toe and heel portions of the member 28. When this member 28 is brought into contact with the lasted shoe in the shank portion, it is bent and the over-all length is shortened so as to bring the toe and 20 heel portions of the lip 28 toward each other. In the subsequent application of pressure between the parts the lip 28 of the lasted shoe will be forced outwardly and beneath the portion 28 around the entire circumference of the shoe, being 25 then in the condition shown in Figure 12, where the interlocking engagement between the sole and the lasted shoe is shown as having been effected.

In some cases it may not be desired to extend 30 the interlocking engagement around the heel end of the shoe and in some cases it may be desired that one or both sides of the shank or waist portion of the shoe present a thinned edge. It is therefore possible to omit the formation of the 35 lips 19 or 21 about the heel or on either or both sides of the shank portion, since at these portions there is no great tendency for the sole to pull away from the lasted shoe, the forepart being that part of the shoe where the most of the 40 strain tending to separate the parts occurs. Where the interlock is not desired, particularly in the shank portion, it is desirable to rough the margin of the outersole where securing by cement is desired, such a roughened area being 45 shown between the points *a*—*b* on one side of the shank in Figure 13. Where this is desired, also, the outersole will not be provided with its inwardly extending lip. Where this lip is made as a separate piece it may be secured to the outer- 50 sole as by cementing, stitching, or other means, and where cementing is employed, it is preferable to rough the adjacent surfaces of the sole and strip in order to effect a better bond, particularly where pyroxylin cement such as is commonly now 55 employed in cement process shoes is used.

In Figures 14, 15 and 16, other forms of inner-sole lip which can be temporarily brought inwardly to facilitate the engagement of the lip with the corresponding portion of the outersole are shown. For example, in Figure 14, the lip is formed from reinforcing layers 30 and 31 of an innersole, together with the upper materials, all being secured together by the stitching 32. In Figure 15 the portions 30 and 31 are employed

but without any other innersole. In Figure 16 no other innersole is employed and the lip is reinforced by a folded layer of leather or the like as at 35 which is secured in position by the stitching 36.

Where an innersole is used, it may also be built up as shown in Figures 8 to 11 to form the marginal rib. In Figure 8 an innersole 38 is employed with a marginal stiffening feather 39 secured thereto. In Figure 10 the innersole 38 is surfaced across its entire width with a reinforcing member 40 which forms the lip. In Figure 9 the innersole 38 and a reinforcing member 41, which may either extend entirely across the innersole or may be merely a marginal strip, as shown in Figure 8, are secured together as by a line of stitching 42. In Figure 11 an innersole 38 is employed reinforced by one or more layers which may be of fabric, or the like, as at 45, and the outer edge of the innersole may be slit inwardly as at 46 so that the portion 47 therebeneath, together with the reinforcing layer or layers 45, forms a portion of the innersole interlocking lip.

In Figures 17, 18 and 19 various forms of outer-sole are illustrated. In Figure 17 a marginal lip 50 is shown as integral with the main body of the outersole 51, while in Figures 18 and 19 the lips are formed of separate pieces secured to the upper face of the outersole. In Figure 18 the marginal strip is shown as made of two parts 52 and 53 suitably secured together, the whole being secured to the outersole 51, as by stitching 54. In Figure 19 the marginal strip is shown as integral but having a flange portion 55 which directly overlays the marginal portion of the sole member 51. These parts may be secured together by cementing, stitching, stapling, or other suitable means. These specific constructions of innersole or lasted shoe lip and outersole per se form no part of the present invention, being shown and claimed in my prior application Serial No. 79,681, filed May 14, 1936.

From the foregoing description of certain embodiments of this invention, it should be evident to those skilled in the art that various further changes and modifications may be made without departing from the spirit or scope of this invention as defined by the appended claim.

I claim:

The method which comprises lasting a shoe and forming beneath the sole face thereof a normally outwardly projecting element extending substantially entirely therearound, providing a flat sole blank of substantially the size for the finished shoe having a marginal inwardly directed lip on its top face, and applying said sole blank in flat condition to the lasted shoe with said element positioned inwardly of said lip and conforming said blank and lip to the longitudinal curvature of the sole face of the lasted shoe thus pulling the toe and heel ends inwardly and forcing said element beneath said lip and securing said element in position.

FRED L. AYERS.
